UNITED STATES PATENT OFFICE.

WALTER B. SMITH AND WILLIAM M. HAMILTON, OF MARLBOROUGH, MASSACHUSETTS.

DESIGN FOR A GAME-BOARD.

SPECIFICATION forming part of Design No. 27,444, dated July 27, 1897.

Application filed May 10, 1897. Serial No. 635,942. Term of patent 34 years.

To all whom it may concern:

Be it known that we, WALTER B. SMITH and WILLIAM M. HAMILTON, citizens of the United States, residing at Marlborough, in the county 5 of Middlesex and State of Massachusetts, have invented and produced a new and original Design for Game-Boards, of which the following is a specification, reference being had to the accompanying drawings, forming 10 a part thereof.

The leading features of the design consist 15 of a game-board rectangular in outline having a beaded periphery, a series of stars, and a series of bars with a series of holes within the stars and bars.

1 represents the frame or body of the game- 20 board.

2 represents the border or framing of the main body 1.

3 represents a rectangular space in the upper left-hand corner of the board containing 25 a number of stars 4 corresponding to the number of States in the Union.

5 represents the thirteen bars of the United States flag extending horizontally, as shown.

6 represents a series of holes in the bars 5.

7 represents the flagstaff of the flag, and 8 30 a conventional scroll or turning up of the bottom of the flag.

The holes 9 and 6 are designed to receive a peg or pegs, in the use of the board, in playing upon the game-board.

9 represents the holes in the stars 4, there being a hole in every star.

The representation of the flagstaff 7 and the scroll 8 may be omitted.

Having described our invention, what we 40 claim as new, and desire to secure by Letters Patent, is—

The design for a game - board substantially as shown and described.

In testimony whereof we hereunto affix our 45 signatures in the presence of two witnesses.

WALTER B. SMITH.

WILLIAM M. HAMILTON.
